UNITED STATES PATENT OFFICE.

WILLIAM N. CRABTREE, OF GLOBE, CALIFORNIA.

BANDAGE-MACHINE.

SPECIFICATION forming part of Letters Patent No. 527,365, dated October 9, 1894.

Application filed April 18, 1894. Serial No. 507,982. (No model.)

To all whom it may concern:

Be it known that I, WILLIAM N. CRABTREE, a citizen of the United States, and a resident of Globe, in the county of Tulare and State of California, have invented certain new and useful Improvements in Bandage-Rollers for Surgeons; and I do declare the following to be a full, clear, and exact description of the invention, such as will enable others skilled in the art to which it appertains to make and use the same, reference being had to the accompanying drawings, and to letters of reference marked thereon, which form a part of this specification.

15 Figure 1 is a front view of the invention, showing a roll of bandage thereon. Fig. 2 is a side elevation of same. Fig. 3 is a perspective view of the invention with spool removed, and the stirrup up. Figs. 4 and 5 are details 20 of disk on end of hollow shaft. Fig. 6 is a side elevation of axis K and disks. Fig. 7 shows the guide. Figs. 8 and 9 are modifications of spool. Fig. 10 is a perspective view 25 of the band hook. Fig. 11 is a detached, perspective view of the stirrup.

This invention has relation to certain new and useful improvements in bandage rollers for surgeons, the object being to provide a device of this character, simple in its construction, convenient in the manner of its operation, and which will completely meet the wants of the surgeon in an instrument of this kind.

With this object in view, the invention consists in the novel construction and combination of parts, all as hereinafter described and pointed out in the appended claims.

Referring to the accompanying drawings, the letter A designates the frame of the device, having centrally attached to one edge thereof a suitable handle A', and having its end portions bent upwardly at substantially right angles to form vertical arms a, a'. In the arm a is formed an open bearing b, which receives one of the journals of the spool B, while the arm a' has a bearing therein for a short shaft or axis C, to which is attached a crank C', and which at its inner end is formed with a transverse slot c, which receives a 45 transverse arm d, on the corresponding end of the spool shaft. To place the spool in the frame it is necessary to first place the arm d in engagement with the said slot c, the oppo-

site end portion or journal of the spool shaft being then inserted in the open bearing b. 55 The engagement of the arm d and slot c provides means whereby the rotation of the crank C' is communicated to the spool, while permitting the spool to be readily inserted and removed. 60

D designates a stirrup-shaped frame, the vertical arms of which are pivoted to the arms a, a', at the points d', d', the horizontal portion of the stirrup as it will hereinafter be termed, being underneath the horizontal arm 65 of the frame A. The said horizontal portion of the stirrup is cut-away or of slotted form, the swinging motion of the stirrup being limited by the engagement of the slot with two set screws E, E. These set screws also 70 serve to adjust respectively a pair of bandage guides F, F, which are made adjustable in longitudinal slots f, f, in the horizontal arm of the frame A at the sides thereof opposite the handle A'. These guides have 75 two-part clamps f', which are arranged to engage with and slide in the said slots, and engaged by said set screws, whereby they may be adjusted to the width of the bandage.

One of the vertical arms of the stirrup has 80 an extension g', which forms a keeper for that end of the spool shaft which engages the open bearing b, and prevents the spool from being removed except when the stirrup is swung to one side. The spool may be of 85 several different forms, as will now be described.

In Fig. 9 I have shown a spool which consists simply of a tapered rod having the arms or projections d at one end portion for engagement with the crank axis, and a small projection h at its central portion for engagement with the bandage to hold it when the formation of the roll is commenced. This form of spool is employed when the surgeon 95 desires to roll a bandage, or several of them, for immediate use, and may be withdrawn after the roll is removed from the winder.

Fig. 8 shows a second form designed to retain the roll for use, and having circular 100 flanges or disks H, near each end between which the bandage is rolled.

Fig. 1 shows a more complete form of spool, comprising a hollow shaft J, having at each end a circular flange or disk J'. This hollow 105 shaft receives an axis K, which near each

end carries a disk K', similar to the disks J', and fitting against the said disks. At the inner face of each disk K', the axis K carries a short arm j, which terminates in a cam shaped head j', arranged to engage with a cavity k in the body portion of a hook device L. This hook device is seated between the two disks J', K', the former being partially cut away to receive it, and is pivotally secured to said disk K' at k'. At one end the axis K has pivotally secured therein a lever M, which takes the place of the arms or projections d in the other forms of spool, being arranged to engage with the crank axis. One arm of this lever carries a spring m, which bears against the outer face of the disk K', and throws the opposite arm of the lever against the disk causing a projection or stud n thereon to engage with a small aperture or cavity n' in the said disk, locking the hook devices in such position that their points do not protrude from between the disks. By pressing upon the spring-carrying arm of said lever, the projection n may be withdrawn from said aperture n'. The axis K now being slightly rotated, by means of the lever M, the cam arms j take a bearing against the hook devices, moving them sufficiently to cause their hooks to project from between the disks. An opposite rotation of the shaft again withdraws said hooks. By engaging the bandage with either one of these hooks it may be temporarily held from unwinding while the surgeon is fixing splints, or otherwise engaged.

P designates a band hook, which may also be employed for holding the bandage, said hook comprising a piece of metal, having hooks p for engagement with the windings of the band upon the spool.

In order to facilitate the introduction of the axis K into the spool it is made in two sections, the adjacent ends of the said sections being formed one with an angular tongue r, and the other with a corresponding socket r', to receive said tongue and thus unite the two sections.

To spool a bandage with any of the forms of spools above described, place the spool in the winder while the stirrup is swung up, pass the bandage through the slot in the stirrup between the two guides. Then close the stirrup down. The bandage is then made fast to the spool, and the crank rotated.

Having thus described my invention, what I claim as new, and desire to secure by Letters Patent, is—

1. In a bandage roller for surgeons, a frame, having open bearings thereon, a spool arranged to removably journal in said bearings, adjustable bandage guides working in said frame, and a stirrup device pivoted to said frame and arranged to temporarily confine the spool in its bearings, substantially as specified.

2. In a bandage roller for surgeons, a frame having vertical arms at each end portion, an

open bearing in one of said arms, a slotted crank axis journaled in the opposite of said arms, a spool having a journal adapted to engage said open bearing and having means for detachably engaging the slot of said axis, and a stirrup pivoted to said arms and having a slotted horizontal portion, substantially as specified. 75

3. A bandage roller for surgeons, comprising a frame having arms at each end, an open bearing in one of said arms, a cranked axis journaled in the opposite of said arms, and having a slot therein, a spool having a journal adapted to engage with the slot of said axis, bandage guides adjustably secured in slots in the body portion of said frame, a stirrup having arms pivoted to the arm of said frame and a slotted base portion, one of said stirrup arms having an extension forming a keeper for the spool journal which engages the said open bearing, substantially as specified. 80

4. In a bandage roller for surgeons, the frame, the adjustable bandage guides in said frame, the slotted stirrup pivoted to said frame, a spool arranged to detachably engage bearings in said frame, a winding crank journaled in said frame, and means for holding the bandage from unwinding from said spool, substantially as specified. 90

5. In a bandage rolling machine for surgeons, a spool having a hollow shaft, a disk on each end of said shaft, an axis passing through said shaft, a hook device pivoted to each of said disks, and cam arms carried by said shaft and engaging said hook devices, substantially as specified. 100

6. In a bandage rolling machine for surgeons, a spool having a hollow shaft, a disk on each end portion of said shaft, a hook device pivoted in a cut-away portion of each of said disks, an axis passing through said hollow shaft and having arms engaging said hook devices, parallel disks carried loosely on said axis, and a lever on one end portion of said axis, substantially as specified. 110

7. In a bandage rolling machine for surgeons, a spool having a hollow shaft, a disk on each end portion of said shaft, a hook device pivoted in a cut-away portion in each of said disks, a two-part axis passing through said hollow shaft, arms carried by said shaft and having cam portions engaging said hook devices, parallel disks loose on said axis, and secured to the spool disks, a lever pivotally held in one end portion of said axis, and having on one arm a projection adapted to engage with one of said parallel disks, and a spring for securing such engagement, said lever being adapted to engage with a winding crank, substantially as specified. 115 120 125

In testimony whereof I affix my signature in presence of two witnesses.
